UNITED STATES PATENT OFFICE.

OSCAR C. ECKLUND, OF PHILADELPHIA, PENNSYLVANIA.

LOOM-STOPPING DEVICE.

Application filed September 26, 1923. Serial No. 685,005.

To all whom it may concern:

Be it known that I, OSCAR C. ECKLUND, a citizen of the United States, residing at Philadelphia, in the county of Philadelphia and State of Pennsylvania, have invented 5 certain new and useful Improvements in Loom-Stopping Devices, of which the following is a specification.

My invention relates to loom stopping devices which are particularly adapted for use 10 in stopping a loom when shuttles occupy both boxes aligned with the race, thereby preventing a shuttle in one box from being shot across the race and smashing into the 15 shuttle in the other box.

Heretofore numerous devices have been tried for stopping a loom when, through inadvertence of the weaver, a shuttle has been placed in each of the boxes aligned with a 20 race. These devices were unsatisfactory for various reasons such as not being sufficiently sensitive to quickly respond and stop the loom, not being reliable for positive operation, not being automatic in resetting them- 25 selves after stopping the loom, not being adjustable to take up wear so as to maintain an accurate setting at all times, and being too complicated and not standing the strains and wear for a reasonable length of 30 time.

The objects of my invention are to provide a loom stopping device which will avoid the above objections and positively stop the loom when, through inadvertence, a 35 shuttle occupies each box aligned with the race; to provide a device which is accurate and positive in its operation at all times; is sensitive to quickly respond and stop the loom; is adjustable to an accurate setting 40 at all times on any type of loom; is automatic to re-set itself after stopping the loom and which is simple and durable in construction.

These objects, and other advantageous 45 ends which will be described hereinafter, I attain in the following manner, reference being had to the accompanying drawings in which—

Figure 1 is a fragmentary top plan view 50 of a loom of the drop box type having my improved loom stopping device applied thereto,

Figure 2 an enlarged fragmentary section on line 2—2 of Figure 1,

55 Figure 3 a vertical section on line 3—3 of Figure 2 showing the lay swung to the end

of its rearward beat where the picking action occurs,

Figure 4 a similar view but showing the lay swung to the end of its forward beat 60 where the changing of the shuttle boxes occurs,

Figure 5 a view similar to Figures 3 and 65 4 showing the lay swung slightly forward and illustrating my improved stopping de- vice about to stop the loom,

Figure 6 an enlarged perspective view of the stopping plates shown in Figure 3,

Figure 7 a section on line 7—7 of Figure 3, 70

Figure 8 a section on line 8—8 of Figure 3, and

Figure 9 a view similar to Figure 3 illustrating how the arcuate edges bridge the recess and notch when they are slid 75 relatively to each other.

In the drawings, 10 indicates the frame of the loom, 11 the breast beam beneath which is arranged a knock-off shaft 12 having a knock off lever 13 fixed to one end and 80 its other end connected to any suitable means for stopping the loom. A lay beam 14 of the batten structure 15 has the ordinary movable shuttle boxes 16 disposed at its opposite ends for receiving shuttles 17 85 which are adapted to be shot across the race of the lay beam by the picker sticks in the usual manner. The shuttle boxes have the usual binders 18.

My improved stopping device includes a 90 trip 19 slidable in upright guide eyes 20 integral with a bracket 21 secured to lay beam 14. The trip is preferably made from a strip of metal and has its upper end bent or folded downward to provide a rounded or 95 tapered part 22 and a shoulder 23. A spring 24, coiled about a pin 25 on trip 19, has its ends 26 extending through lugs 27 on bracket 21. This spring 24 tends to move trip 19 downward when it is released 100 by mechanism now to be described. Shoulder 23 rests on bent ends 28 of arms 29 adjustable lengthwise in heads 30 which are rotatably adjustable on the inner ends of rods 31. These rods 31 are rockably 105 mounted in bearings 32 on bracket 21 and bearings 33 on lay beam 14. Torsion springs 34 are coiled about rods 31, one end of each spring engaging lay beam 14 and the other end being connected to a collar 35 110 adjustably secured on rod 31. The outer ends of rods 31 carry heads 36 rotatably ad-

justable thereon similar to heads 30. Fingers 37 are adjustable lengthwise in heads 36 and are provided with humps 38 adapted to slidably engage binders 18 of the shuttle boxes aligned with the race. Torsion springs 34 normally keep humps 38 in engagement with binders 18.

A bracket 39, provided with vertical slots 40, is adjustably mounted on breast beam 11 by lag bolts 41 passing through the slots and screwed into the breast beam. A non-slidable plate 42, provided with a boss 43, is adjustably mounted for swinging movement on bracket 39 by a bolt 44 which passes through the boss and bracket and has its head set in a counter-bore 45 within the boss. The shank 46 of the bolt is angular at 47 and fits within an angular opening 48 in boss 43 to prevent turning of the bolt when adjusting plate 42. The upper edge 49 of the non-slidable plate 42 is arcuate, the arc being described from the center of the pivotal support on which the batten structure 15 swings. In this arcuate edge 49 is a recess 50 which forms a camming surface 51 on which trip 19 rides. A plate 52 is slidably mounted on plate 42 preferably by providing slots 53 in plate 52 for slidably receiving projections 54 on plate 42. A screw and washer may be provided to hold plate 52 against plate 42 as shown at 55. Slidable plate 52 has an arcuate upper edge 56, corresponding to the arcuate upper edge 49 on non-slidable plate 42. A ratchet notch 57 in arcuate edge 56 provides a shoulder 58 to be engaged by trip 19 when it is about to stop the loom. The top of shoulder 58 is rounded or tapered as shown at 59 so that trip 19, in normally passing over the shoulder will not engage it. A slotted member 60 is adjustably connected to the rear end 61 of plate 52. The loom stopping mechanism is connected to this slotted member by an arm 62 fixed on knock-off shaft 12 and provided with a pin 63 which slides in slot 64 of the slotted member. Thus slidable plate 52 is directly connected with the loom stopping mechanism and moved along with it when it is actuated to start or stop the loom while non-slidable plate 42 is fixed to the loom.

In attaching my improved stopping device to a loom, bracket 39 is bolted to breast beam 11 by lag bolts 41 and adjusted to the desired height by the lag bolts which pass through slots 40 in the bracket, and slidable plate 52 is connected to arm 62 on the knock-off shaft. Trip 19 and its associated parts are attached to lay beam 14 so that humps 38 on fingers 37 will engage binders 18, and bent ends 28 will be under shoulder 23.

Plates 42 and 52 are adjusted by loosening the nut on bolt 44 and swinging the plates up or down until their arcuate edges

coincide with an arc described by the swinging movement of the lower edge of trip 19. In other words, the adjustment is such that the arcuate edges of plates 42 and 52, when in the position shown in Figure 3, will barely clear the lower end of trip 19 when the lay beam swings to and from the position shown in Figure 4.

The arcuate edges will, regardless of the position in which the weaver stops the lay beam, always hold trip 19 in its upper or inoperative position while the weaver is manipulating the shuttles in the boxes thereby causing bent ends 28 to swing free of shoulder 23 on the trip. For example, suppose that the loom is stopped by the knock-off lever at a point where trip 19 will be directly above recess 50 or notch 57, the knock-off lever, being connected to slidable plate 52, will slide it relatively to non-slidable plate 42, so that recess 50 will be bridged by the arcuate edge 56 and notch 57 by the arcuate edge 49, thus leaving the arcuate edges 49 and 56 so that they form a practically continuous arcuate edge bridging recess 50 and notch 57 as shown in Figure 9.

If the weaver should manipulate the shuttles in the boxes so as to cause bent ends 28 to swing free of shoulder 23 and release trip 19 when it is directly above recess 50, arcuate edge 56 bridging recess 50, will prevent the trip from dropping therein and hold it in its upper position. Similarly if the trip is stopped directly above notch 57, arcuate edge 49 bridging it will prevent the trip from dropping therein and hold it in its upper position. After the weaver has properly set the shuttles in the boxes, the bent end 28 leading from the empty shuttle box will engage shoulder 23 and hold trip 19 in its upper position, while the other bent end 28, which leads from the occupied shuttle box, will remain free of shoulder 23. The loom may then be started again by moving the knock-off lever into its former position. This will move slidable plate 52 and bring notch 57 opposite recess 50 which again places my improved stopping device in set position for stopping the loom. Thus trip 19 is always held in its upper position while the weaver manipulates the shuttles and until one of the bent ends 28 engages under shoulder 23.

If the weaver should leave a shuttle in each box aligned with the race, both bent ends 28 will remain free of shoulder 23, leaving trip 19 free to slide downward. When the loom is started by moving the knock-off lever into its starting position, notch 57 will be moved by the knock-off lever adjacent notch 50 and trip 19 will drop into notch 57. A continued movement of the lay will move trip 19 into engagement with shoulder 58 and slide plate 52 relatively to plate 42 and actuate the stopping

means to again stop the loom. After the stopping action occurs, the loom and lay beam are moved a short distance by inertia. I have therefore made the length of recess 50 so that the distance the lay beam moves will just move trip 19 over camming face 51 and reset the device. Thus if the weaver should neglect to properly set the shuttles in the boxes, the loom will be stopped and the device reset, thereby preventing the shuttle in one box from smashing into the shuttle in the oppositely aligned box.

A stopping device constructed with an arcuate edge equal to an arc described by the swinging movement of the lower edge of the trip and being adjustable so that an accurate setting may be maintained at all times, is readily adapted to operate in conjunction with a slidable trip. The slidable trip is essential to make the stopping device sensitive because the binders are moved only a slight distance about an $\frac{1}{8}$ of an inch, by the shuttles, and it requires very little movement of the binders to release a slidable trip which has practically no friction in its movement downward to engage shoulder 58 and stop the loom. The non-slidable plate 42 and slidable plate 52, having corresponding arcuate edges, produce a practically continuous arcuate edge when the plates are slid, relatively to each other, from their normal to their loom stopping position so that the lay beam may be stopped at any point in its movement without the trip dropping down in recess 50 or notch 57 while the weaver is manipulating the shuttles in the boxes.

While I have described my invention as taking a particular form, it will be understood that the various parts may be changed without departing from the spirit hereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

50 1. In combination with a loom having a breast beam, stop mechanism, batten structure and shuttle boxes; a non-slidable plate secured to the breast beam and having an arcuate edge interrupted by a cam face; a plate mounted to slide relatively to the non-slidable plate and having an arcuate edge interrupted by a shoulder; means connecting the slidable plate with the stop mechanism; a trip on the batten structure adapted to engage the shoulder and cam face if released before the loom stops, and be held in raised position by the arcuate edges if released after the loom stops, and means co-operating with the shuttle boxes for holding and releasing the trip.

2. In combination with a loom having a breast beam, stop mechanism, batten structure and shuttle boxes; a non-slidable plate secured to the breast beam for vertical and swinging adjustment and having an arcuate edge interrupted by a cam face; a plate mounted to slide relatively to the non-slidable plate and having an arcuate edge interrupted by a shoulder; means connecting the slidable plate with the stop mechanism; a trip on the batten structure adapted to engage the shoulder and cam face if released before the loom stops, and be held in raised position by the arcuate edges if released after the loom stops, and means co-operating with the shuttle boxes for holding and releasing the trip.

70 3. In combination with a loom having a breast beam, stop mechanism, batten structure and shuttle boxes; a non-slidable plate secured to the breast beam and having an arcuate edge interrupted by a cam face, the arcuate edge coinciding with an arc described from the center of the pivotal support for the batten structure; a plate mounted to slide relatively to the non-slidable plate and having a corresponding arcuate edge interrupted by a shoulder; means connecting the slidable plate with the stop mechanism; a trip on the batten structure adapted to engage the shoulder and cam face if released before the loom stops, and be held in raised position by the arcuate edges if released after the loom stops, and means co-operating with the shuttle boxes for holding and releasing the trip.

80 4. In combination with a loom having a breast beam, stop mechanism, batten structure and shuttle boxes; a non-slidable plate secured to the breast beam and having a recess in its upper edge forming a cam face; a plate mounted to slide relatively to the non-slidable plate and having a notch in its upper edge forming a shoulder; means connecting the slidable plate with the stop mechanism; a trip on the batten structure adapted to engage the shoulder and cam face if released before the loom stops, and be held in raised position by the upper edges of the plates if released after the loom stops, and means co-operating with the shuttle boxes for holding and releasing the trip.

90 5. In combination with a loom having a breast beam, stop mechanism, batten structure and shuttle boxes; a non-slidable plate secured to the breast beam and having an arcuate upper edge interrupted by a recess forming a cam face; a plate mounted to slide relatively to the non-slidable plate and having an arcuate upper edge interrupted by a notch forming a shoulder; means connecting the slidable plate with the stop mechanism; a trip on the batten structure adapted to engage the shoulder and cam face if released before the loom stops, and

100 105 110 115 120 125 130

means co-operating with the shuttle boxes for holding and releasing the trip.

be held in raised position by the arcuate edges if released after the loom stops, and means co-operating with the shuttle boxes for holding and releasing the trip.

- 5 6. In combination with a loom having a breast beam, stop mechanism, batten structure and shuttle boxes; a non-slidable plate secured to the breast beam and having an arcuate edge interrupted by a cam face; a 10 plate mounted to slide relatively to the non-slidable plate and having an arcuate edge interrupted by a shoulder; means connecting the slidable plate with the stop mechanism; a slidable trip on the batten structure adapted to engage the shoulder and cam face if released before the loom stops, and be held in raised position by the arcuate edges if released after the loom stops, and means co-operating with the shuttle boxes for holding 15 and releasing the trip.

- 20 7. In combination with a loom having a breast beam, stop mechanism, batten structure and shuttle boxes; a non-slidable plate secured to the breast beam and having an arcuate edge interrupted by a recess forming a cam face; projections on the side of the plate; a plate having slots slidable on the projections and provided with an arcuate edge interrupted by a notch forming a shoulder; means connecting the slidable plate to the stop mechanism; a trip on the batten structure adapted to engage the shoulder and cam face if released before the loom stops, and be held in raised position by the 25 arcuate edges if released after the loom stops, and means co-operating with the shuttle boxes for holding and releasing the trip.

- 30 8. In combination with a loom having a breast beam, stop mechanism, batten structure and shuttle boxes; a non-slidable plate secured to the breast beam and having an arcuate edge interrupted by a recess forming a cam face; projections on the side of the plate; a plate having slots slidable on the 35 projections and provided with an arcuate edge interrupted by a notch forming a shoulder; means connecting the slidable plate to the stop mechanism; a trip slidable on the batten structure adapted to engage the shoulder and cam face if released before the loom stops, and be held in raised position by the arcuate edges if released after the loom stops, and means co-operating with the shuttle boxes for holding and releasing the trip.

- 40 9. In combination with a loom having a breast beam, stop mechanism, batten structure and shuttle boxes; a bracket mounted on the breast beam for vertical adjustment; a non-slidable plate mounted on the bracket for swinging adjustment and having an arcuate edge interrupted by a cam face; a 45 plate mounted to slide relatively to the non-slidable plate and having an arcuate edge interrupted by a shoulder; means connect-

50 ing the slidable plate to the stop mechanism; a trip on the batten structure adapted to engage the shoulder and cam face, and means co-operating with the shuttle boxes for holding and releasing the trip.

55 10. In combination with a loom having a breast beam, stop mechanism, batten structure and shuttle boxes; a bracket having vertical slots; bolts passing through the slots for securing the bracket to the breast beam; a non-slidable plate mounted on the bracket for swinging adjustment and having an arcuate edge interrupted by a cam face; a 60 plate mounted to slide relatively to the non-slidable plate and having an arcuate edge interrupted by a shoulder; means connecting the slidable plate with the stop mechanism; a trip on the batten structure adapted to engage the shoulder and cam face, and means co-operating with the shuttle boxes 65 for holding and releasing the trip.

70 11. In combination with a loom having a breast beam, stop mechanism, batten structure and shuttle boxes; a bracket mounted on the breast beam for vertical adjustment; a non-slidable plate having an arcuate upper edge interrupted by a cam face; a bolt fixed to the plate for adjustably securing the plate to the bracket; a plate mounted to slide relatively to the non-slidable plate and having an arcuate edge interrupted by a shoulder; means connecting the slidable plate with the stop mechanism; a trip on the batten structure adapted to engage the shoulder and cam face, and means co-operating with the 75 shuttle boxes for holding and releasing the trip.

80 12. In combination with a loom having a breast beam, stop mechanism, batten structure and shuttle boxes; a bracket mounted on the breast beam for vertical adjustment and having an opening; a non-slidable plate having an arcuate upper edge interrupted by a cam face; a boss on the plate having a counter-bore and an angular opening; a securing bolt having an angular part fitting within the angular opening and passing through the opening in the bracket for adjustably securing the plate to the bracket; a plate mounted to slide relatively to the non-slidable plate and having an arcuate edge interrupted by a shoulder; means connecting the slidable plate with the stop mechanism; a trip on the batten structure adapted to engage the shoulder and cam face, and means co-operating with the shuttle boxes 85 for holding and releasing the trip.

90 13. In combination with a loom having a batten structure and shuttle boxes; a bracket having guide eyes secured to the batten structure; a trip having a shoulder on its upper end slidable within the guide eyes; a pin on the trip; a spring coiled around the pin and having its ends connected with the 95 opposite sides of the bracket for moving the 100

trip downward; means co-operating with the shuttle boxes for engaging the shoulder to hold the trip in its upper position, and means co-operating with the trip for stopping the loom.

14. In combination with a loom having a batten structure and shuttle boxes; a trip having a shoulder in its upper end slidable on the batten structure; rods rockably mounted on the batten structure; arms mounted on the inner ends of the rods for adjustment about the axis of the rods and for adjustment radially of the rods and having bent upper ends engaging the shoulder; means on the outer ends of the rods co-operating with the shuttle boxes to move the arms and release the trip, and means co-operating with the trip for stopping the loom.
15. 15. In combination with a loom having a batten structure and shuttle boxes; a trip having a shoulder in its upper end slidable on the batten structure; rods rockably mounted on the batten structure; heads adjustably mounted on the inner ends of the rods; arms adjustably mounted on the heads and having bent upper ends engaging the shoulder; heads adjustably mounted on the outer ends of the rods; fingers having humps engaging the shuttle boxes adjustably mounted in said heads, and means co-operating with the trip for stopping the loom.
- 20 16. In combination with a loom having a batten structure and shuttle boxes; a trip having a shoulder in its upper end slidable on the batten structure; rods rockably mounted on the batten structure; heads adjustably mounted on the inner ends of the rods; arms adjustably mounted on the heads and having bent upper ends engaging the shoulder; means on the outer ends of the rods co-operating with the shuttle boxes to move the arms and release the trip, and means co-operating with the trip for stopping the loom.
- 25 17. In combination with a loom having a batten structure and shuttle boxes; a bracket, having guide eyes and lugs provided with openings, secured to the batten structure; a trip provided with a shoulder in its upper end slidable in the guide eyes; a coiled spring connected to the trip and having its ends extending through the openings; means co-operating with the shuttle boxes for engaging the shoulder to hold the trip in its upper position, and means co-operating with the trip for stopping the loom.

the shoulder; fingers mounted on the outer ends for adjustment about the axis of the rods and for adjustment radially of the rods and having humps engaging the shuttle boxes for removing the arms to release the trip, and means co-operating with the trip for stopping the loom.

18. In combination with a loom having a batten structure and shuttle boxes; a trip having a shoulder in its upper end slidable on the batten structure; rods rockably mounted on the batten structure; heads adjustably mounted on the inner ends of the rods; arms adjustably mounted on the heads and having bent upper ends engaging the shoulder; heads adjustably mounted on the outer ends of the rods; fingers having humps engaging the shuttle boxes adjustably mounted in said heads, and means co-operating with the trip for stopping the loom.

19. In combination with a loom having a batten structure and shuttle boxes; a bracket, having guide eyes and lugs provided with openings, secured to the batten structure; a trip provided with a shoulder in its upper end slidable in the guide eyes; a coiled spring connected to the trip and having its ends extending through the openings; means co-operating with the shuttle boxes for engaging the shoulder to hold the trip in its upper position, and means co-operating with the trip for stopping the loom.

In testimony whereof I have signed my name to this specification in the presence of two subscribing witnesses.

OSCAR C. ECKLUND.
